UNITED STATES PATENT OFFICE.

WILLIAM PLATTO, OF POUGHKEEPSIE, NEW YORK.

WAGON-BRAKE.

SPECIFICATION forming part of Letters Patent No. 441,774, dated December 2, 1890.

Application filed March 19, 1890. Serial No. 344,540. (No model.)

To all whom it may concern:

Be it known that I, WILLIAM PLATTO, a citizen of the United States, residing at Poughkeepsie, in the county of Dutchess and State 5 of New York, have invented certain new and useful Improvements in Wagon-Brakes, of which the following is a specification.

My invention relates to improvements in wagon-brakes; and it consists in certain novel 10 features of the operating mechanism, as will be hereinafter described and claimed.

In the accompanying drawings, which fully illustrate my invention, Figure 1 is a bottom plan view of a wagon-body, showing my improved brake in position thereon. Fig. 2 is 15 an elevation of the front end of the wagon-body, showing the mechanism for applying the brake; and Fig. 3 is a longitudinal section.

20 Referring to the drawings by letter, A designates the wagon-body, which may be of any desired size or construction, and has the brake-levers B B fulcrumed on its under side, as shown. These brake-levers are provided at 25 their inner ends with the adjustable arms C C, so that they may be readily adapted to the width of the wagon-body, and said arms C C are constructed with eyes D at their extremities.

30 E E designate two longitudinally-disposed parallel rods, which have their front ends secured to a reciprocating yoke F and their rear ends fitted in the eyes D at the ends of the arms C. The yoke F is mounted between 35 two plates G G, secured to the bottom of the wagon-body, and it is provided on its inner opposing sides with the racks H, as clearly shown.

40 Intermeshing cog-wheels I I are journaled in the plates G G between the sides of the yoke and mesh with the racks H, so that when the cog-wheels are rotated the yoke will be caused to slide forward or backward.

45 The journal or axle of one of the cog-wheels is extended above the upper plate and is made angular, so as to be readily engaged by the angular socket J in the lower end of the shaft K, which is mounted vertically on the front end of the wagon-body.

50 This shaft K is journaled in the brackets or bearings L, secured in the dash-board of the vehicle, and is provided with a pinion M near

its upper end. This pinion M meshes with a crown-wheel N, which is mounted on a standard or supporting-plate O, and is provided 55 with a handle or lever P, secured rigidly to its rear side and projecting upward to a point where it will be in convenient reach of the driver. A curved plate or ratchet-bar Q is arranged above the wheel N and concentric 60 therewith, and is engaged by a pawl R, pivoted on the lever or handle P, so as to hold the device in any position to which it may be adjusted. If so desired, the lever or handle may be made to project horizontally to one 65 side, as indicated at S, in order that the device may be operated by the foot instead of by hand.

T designates a spring, which is secured to the bottom of the wagon-body and to the 70 front end of the yoke, so as to draw the same normally rearward and thereby remove the brake-shoes from the wheels.

The operation of the device will be readily understood from the foregoing description, 75 taken in connection with the accompanying drawings. The spring normally draws the yoke backward, so as to throw the outer ends of the brake-levers forward, and thereby keep the brake-shoes from the wheels. When 80 it is desired to apply the brake, the pawl is released from the ratchet-bar by the pressure of the foot, and the lever or handle is then moved to one side, so as to rotate the crown-wheel and thereby impart motion to 85 the vertical shaft. The intermeshing cog-wheels will thus be caused to act on the racks and slide the yoke forward, consequently applying the brake-shoes to the 90 wheels. The pressure on the pawl is then released and the shoes will be held against the wheels. Upon disengaging the pawl from the ratchet-bar the spring automatically releases the shoes from the wheels.

It will be observed that my device is composed of few parts, which are compactly arranged and are thoroughly protected against injury. The device operates positively and easily, and its advantages are thought to be 95 obvious.

Having thus described my invention, what I claim, and desire to secure by Letters Patent, is—

1. The combination of brake-levers hav-

ing adjustable arms at their inner ends, the yoke having rack-teeth on its inner opposing sides, connections between the yoke and brake-levers, intermeshing cog-wheels arranged within the yoke and meshing with the rack-teeth thereon, and means for rotating said cog-wheels, substantially as set forth.

2. The combination of the brake-levers, the vertical shaft having a pinion near its upper end, connections between said shaft and the brake-levers, the crown-wheel meshing with the pinion, the lever secured rigidly to and projecting from the crown-wheel, the ratchet-bar arranged concentrically with the

crown-wheel, and the pawl pivoted on the lever and engaging the ratchet-bar, as set forth. 15

3. The combination of the brake-levers, the yoke having rack-teeth on its inner opposing sides, connections between the yoke and the brake-levers, intermeshing cog-wheels arranged within the yoke and meshing with the racks thereon, and means for rotating said cog-wheels, as set forth. 20

WILLIAM PLATTO.
